UNITED STATES PATENT OFFICE.

LOUIS YIELKY, OF ROCK CREEK, KANSAS.

DISK MARKER.

SPECIFICATION forming part of Letters Patent No. 616,279, dated December 20, 1898.

Application filed June 27, 1898. Serial No. 684,549. (No model.)

To all whom it may concern:

Be it known that I, LOUIS YIELKY, of Rock Creek, Jefferson county, Kansas, have invented certain new and useful Improvements 5 in Two-Row Disk Markers, of which the following is a specification.

My invention relates to what I term "two-row disk markers" for turning a furrow on plowed ground—that is, performing the work 10 of a single plow or lister; and it consists in certain novel and peculiar features of construction and combinations of parts, as will be hereinafter described and claimed.

The object of the invention is to produce a 15 machine of this character which may be adjusted to accommodate rows of different widths and whereon the furrow-turning disks may be adjusted to vary the width or depth 20 of the furrow.

A further object is to produce a machine of 25 this character which is simple, strong, durable, and inexpensive of construction.

In order that the invention may be fully understood, I will proceed to describe it with 30 reference to the accompanying drawings, in which—

Figure 1 is a side elevation. Fig. 2 is a 35 top plan view. Fig. 3 is a rear view showing the relation between a pair of the disks. Fig. 4 is a top plan view of the same on a larger scale, the scraper-arms being shown in section. Fig. 5 is a vertical section taken between the disks. Fig. 6 is a central transverse section. Fig. 7 is a top plan view of 40 the disk-adjusting plates. Fig. 8 is a view illustrating the relation existing between a disk and scraper.

In the said drawings, 1 designates a substantially horizontal U-shaped frame having 45 its rear ends connected by a cross-bar 1^a, carrying axle-stubs 1^b, provided with wheels 1^c, which not only serve to support the operative parts above the ground in traveling to and from the field, but also act as a guide to regulate the depth of cut.

2 designates a vertically-arranged U-shaped frame externally embracing frame 1 and secured thereto, as shown at 3. Said frame carries the tongue 4, and secured to the latter 50 is the standard 5, carrying seat 6.

An oblong rectangular frame is constructed as follows:

7 designates a transverse angle-iron ar-

ranged a suitable distance below the frame 1 and slightly rearward of the frame 2.

55

8 designates a pair of longitudinally-extending bars having their rear ends bent downward, substantially like the ordinary shank of a cultivator, but provided at their front ends with the inwardly-turned slotted arms 9, which rest upon the horizontal flange of said angle-iron and are adjustably bolted to the vertical flange of said iron, as shown at 10. A pair of angle-brackets consist of the arms 11, bolted to the inner sides of bars 8, 60 as shown at 13, and the transverse slotted arms 12, which overlap each other and are adjustably secured together by means of the clamping-bolts 14. By this arrangement it is obvious that said oblong rectangular frame 65 may be lengthened or shortened in order to accommodate the machine to rows of varying widths.

70

15 designates a substantially U-shaped bail which is pivoted in the lower ends of 75 frame 2, and 16 a clip uniting said bail and the doubletree 17.

The oblong rectangular frame above described is provided at its front end with brackets 18, pivotally mounted upon the bail coincidentally with the pivotal point of the latter in the frame 2, as shown clearly in Fig. 1, and 19 designates inclined braces which are secured at their lower ends to the lower end of the said frame and at their upper ends 85 to the tongue.

20 designates the curved shanks of the cultivating and in this instance subsoil shovels 21, said shanks being secured to the bars 8, as shown at 20^a, or in any other suitable 90 manner.

In this machine there are two sets of furrow-turning disks or markers, one set in advance of each subsoil-shovel 21, and as said sets are of duplicate construction a description of one will suffice for both.

Referring now to Sheet 2 particularly, 22 and 23 designate a pair of companion disk-adjusting plates, said plates being provided with inwardly-projecting overlapping base-flanges 22^a and 23^a, respectively, and said flanges are provided with central registering apertures 24 and with segmental slots 25, the slots of one flange registering with those of the other and all struck from the center of 105 the apertures 24. The clamping-bolts 26 ex-

tend through said registering slots, and by means of said bolts the disk-adjusting blocks may be clamped at any desired point of adjustment—that is to say, may be clamped so as to cause their side margins to converge forwardly more or less, as shown, to extend parallel or to diverge forwardly, if ever necessary or desirable. A pivot-bolt 27 extends through the registering opening 24, and upon 5 said bolt the adjustment is made. Just above said flanges 22^a and 23^a the blocks are provided with segmental grooves 28, extending concentrically of said bolt and with grooves 29 in their side edges, said grooves being substantially T-shaped in cross-section (see Fig. 6) and enlarged at one end, as shown at 30, (see Fig. 5,) as will hereinafter appear. 10 31 designates a standard which is provided with a pair of parallel arms 32, which embrace 20 loosely opposite sides of the lower end of the bar 8 (see Fig. 5) and are pivoted near their lower ends to the lower end of said bar, as shown at 32^a. They are also provided with a series of holes 32^b in their upper ends, arranged concentrically of the pivot-bolt 32^a, 25 and extending through the bar 8 and through one or another of the sets of holes 32^b is a bolt 33. When this bolt occupies the middle hole 32^b, the standard is vertical. When it occupies 30 the hole to the rear of hole 32^b, the standard is tilted forwardly, so as to rotate the disks hereinafter described a certain distance in the direction indicated by the arrow, Fig. 5, and when the bolt occupies the opening 35 forward of the central hole it is obvious that the standard will be tilted rearward and downward, and the disk therefore rotatably adjusted in the opposite direction to that indicated by the arrow. The standard is also 40 provided with an enlarged circular base 34, which rests upon the flange 22^a and engages the segmental grooves 28 of said blocks. (See Figs. 3, 4, and 6.) To still further secure said standard in position, it is engaged by the 45 pivot-bolt 27. The base-flange of said standard is provided with a pair of longitudinally-alined lugs 35, which overlap the slots 25 of the blocks, and through said lugs the clamping-bolts 26 also extend. 50 36 designates bolts provided with rectangular heads 37, and one of said bolts projects outwardly from and at right angles to the side of each block 22 and 23. To secure said bolts in position, their heads are first slipped into the grooves by way of the enlargements 30 and then slid forward in a manner which will be readily comprehended. 55 38 designates the scraper-arm or standard mounted upon each bolt 36, and said standards are provided at their upper ends with the angle-knives 39, said knives being provided with slots 40, through which clamping-bolts 40^a of arms 38 extend. By this arrangement the knives may be adjusted toward or from 60 said arms, as will be readily understood by reference to Fig. 8. Said arms are provided at their lower ends and inner sides with

grooves 41 and at their outer sides with sockets 42, the former fitting snugly over the adjacent disk-adjusting blocks. 70

43 designates the disks, which are provided with hubs consisting of an outer section 44 and an inner section 45, secured together and to the interposed disk by means of the bolts or rivets 46, and the inner end of said hub is 75 grooved or turned out, as shown at 47.

48 designates a sleeve mounted upon each rod 36, and journaled thereon are the disks 43.

As the inner ends of the disk "hubs" which project into the sockets 42 of the scraper-arms 80 38 occupy the same vertical plane, practically, as the corresponding ends of said sleeves a ball race or chamber is provided at this point, due to the existence of the grooves 47 in the inner ends of said hubs, and occupying 85 said chamber or groove are a series of bearing-balls 49, which by their position receive the end thrust or pressure of the disk hubs, and thereby reduce friction to the minimum at this point. 90

A dust-proof cap 50 fits over the outer end of each disk hub, and a clamping-nut 51, engaging the bolt 36 and bearing against the outer side of said cap, holds the disk reliably in position. 95

From the foregoing it will be apparent that as the bolts 36, upon which the disks are mounted, project at right angles from the blocks said disks are parallel as long as the blocks remain in the same condition, but may 100 be brought nearer together at their front edges, or, in other words, may be caused to converge by rotating said blocks inward and forward upon the pivot-bolts 27, as illustrated in Figs. 4 and 7 most clearly. If their front 105 edges cannot be brought sufficiently close together by this adjustment, the distance between said edges may be still further reduced by sliding the bolts 36 forward in the slots 29, as indicated, for example, in dotted lines *a*, 110 Fig. 4. If this adjustment does not bring the cutting edges of the disks sufficiently close, they may be brought still nearer by rotatably operating them. To make this latter 115 operation clear, it is desirable to state that the edges of the disks nearest together after the two previous adjustments are those which 120 lie in the horizontal plane of the centers of the disks, as at *b*, Fig. 5. Therefore to bring nearer together the cutting edges, which are of course 125 always vertically below the disks' axes, the rotation of the disks from the position indicated by *b*, Fig. 5, to the position indicated by *c*, same figure, will obviously cause the distance between the cutting edges to be correspondingly 130 narrowed, as the narrowest space between the disks—viz., at *c*—is nearer to the cutting-plane than it was before such rotatable adjustment. The relation between the disks 43 and the 135 scrapers 39 is such that the latter prevent the accumulation of dirt on the outer or exposed surface of the former, and thereby keep them in good operative condition.

In practice as the machine is drawn across

the field said disks, properly adjusted, not only cut down any growing weeds in their path, but also turn a furrow and expose the subsoil, which is acted on with more effect than could be obtained if the marking-disks or furrow-turners were not employed.

The width of the furrow of course is determined by the angle of the disks, and said disks may be caused to cut and the shovels to cultivate more deeply by mechanism described as follows: 52 designates a transverse shaft journaled on the frame 1 and provided with a pair of crank-arms 53, connected by links 54 to the bars 8 of the pivoted disk and shovel-carrying frame. A lever 55, mounted upon said shaft, is provided with the customary spring-actuated dog 56, for engagement with the sector 57 upon frame 1, and also with a pivoted grip 58, connected to said dog to withdraw it from engagement with said sector. When going to or returning from the field, said lever may be manipulated so as to raise the disks and shovels to an inoperative position, as will be readily seen.

From the above description it will be apparent that I have produced a machine of the character described which embodies the features of advantage enumerated as desirable; and it is to be understood that I reserve the right to make such changes as do not involve a departure from the spirit and scope or sacrifice any of the advantages of my invention.

Having thus described the invention, what I claim as new, and desire to secure by Letters Patent, is—

1. In a machine of the character described, a pair of blocks pivoted together, and means to secure them in any desired relation, disks carried by and adjustable along the sides of said blocks, a standard, arms secured to said blocks and pivoted to said standard, and means to secure said arm at an angle to said standard when desired, substantially as described.

2. In a machine of the character described, the combination of a pair of blocks pivoted together and provided with grooves in their outer edges, bolts slidingly and non-rotatably mounted in said grooves, and cutting-disks journaled thereon, substantially as described.

3. In a machine of the character described, the combination of a pair of blocks pivoted together and provided with grooves in their outer edges, bolts having their headed ends retained slidably and non-rotatably in said grooves, cutting-disks journaled on said bolts, scraper-carrying standards having sockets at one side to receive the disk hubs and grooves at the opposite side to receive the grooved edges of the blocks, substantially as described.

4. In a machine of the character described, a frame 1, a cross-bar 1^a, axle-stubs 1^b secured to frame 1, and cross-bar 1^a, wheels upon said axle-stubs, a frame 2, secured to frame 1, and supporting a tongue and seat, in combination with an expandible frame, the same consist-

ing of cross-bar 7, longitudinal bars 8, terminating in curved shanks and provided with slotted angle-arms 9, adjustably secured to cross-bar 7, angle-brackets adjustably connected together and to arms 8, a bail 15, pivotally connected to frame 2, braces 19 between the tongues and said frame 2, and means for pivotally raising said expandible frame upon the frame 2, substantially as described.

5. In a machine of the character described, a pair of rearwardly-projecting bars, a standard pivoted to each bar, and a pair of disks supported from each standard, so that the pivotal operation of said standard will cause the rotatable operation of said disks, substantially as described.

6. In a machine of the character described, a pair of rearwardly-projecting bars, a standard pivoted to each bar and adapted to be set at an angle thereto, a pair of rotatable blocks connected to each standard so as to partake of such inclination, and disks carried by said blocks, substantially as described.

7. In a machine of the character described, a pair of rearwardly-projecting bars, a standard pivoted to each bar and adapted to be set at an angle thereto, a pair of rotatable blocks connected to each standard so as to partake of such inclination, disks carried by said blocks, and scraper-carrying arms clamped between said blocks and the hubs of said disks, substantially as described.

8. In a machine of the character described, a pair of rearwardly-projecting bars, a standard pivoted to each bar and adapted to be set at an angle thereto, a pair of rotatable blocks connected to each standard so as to partake of such inclination, disks carried by and longitudinally adjustable on said blocks, and scraper-carrying arms adjustable with said disks and clamped between their hubs and said blocks, substantially as described.

9. In a machine of the character described, a pair of rearwardly-projecting bars, standards carried thereby, blocks connected to said standards and provided with longitudinal grooves in their sides, headed bolts mounted in said grooves, sleeves mounted upon said bolts, disks journaled in said sleeves and provided with grooves at their inner ends, scraper-carrying arms mounted upon said bolts and provided with grooves at their inner sides embracing said blocks, and with sockets at their outer sides embracing the inner ends of said hubs, bearing-balls occupying said grooves, dust-caps embracing the outer ends of the disk hubs, and clamping-nuts upon said bolts and bearing against said caps, substantially as described.

In testimony whereof I affix my signature in the presence of two witnesses.

LOUIS YIELKY.
